Application June 15, 1945, Serial No. 599,616

In Great Britain June 16, 1944

13 Claims. (Cl. 178—92)

1

The present invention has reference to improvements in and relating to telegraphic receiving apparatus or instruments either of the direct printing type or of the type which perforates holes in a paper tape in accordance with received signals in the Wheatstone (Morse) system of signalling; and it has for its primary object the full utilisation of advantages which are inherent in this system of signalling but which have not hitherto been employed in instruments of the above types.

It is a characteristic feature of the Morse code that the elements of this code, viz. dots, dashes, letter spaces and word spaces are uneven multiples of the shortest signal, the dot; this being one unit long a dash and a letter space are each three units long, and a word space is either five or seven units long. In addition the spaces between the elements in any combination forming a character are each one unit long.

If the moments at which changes from spacing to marking, or from marking to spacing, may occur are denoted by numerals 1, 2, 3, etc., changes from spacing to marking can, for instance, only take place for perfect signals at moments denoted by uneven numerals and changes from marking to spacing can then only take place at moments denoted by even numerals.

According to the present invention signals which would effect changes out of perfect Wheatstone timing are not recorded by the provision in the instrument of means adapted alternately to confine the instrument to the acceptance of (a) changes from marking to spacing only and (b) changes from spacing to marking only, the periods during which the instrument is able to accept the changes (a) being substantially equal to the periods during which the instrument is able to accept the changes (b).

The invention also comprises the provision in a telegraph receiving instrument of selective means associated with the signalling relay of the instrument on the one hand and with the marking and spacing elements of the instrument on the other hand in such a manner as alternately to select the marking elements and the spacing elements for co-operation with said elements to cause signals to be recorded, the arrangement being such that selections due to changes from spacing to marking can only occur during certain intervals which alternate with and are equal to other intervals during which selections due to changes of the opposite kind only can occur.

It is a special feature of the invention that selective members are used which, once released during their respective periods, become inde-

pendent of the operating mechanism—for instance a power relay—and cannot again be retracted by a reversal of the said mechanism. In this way it is possible to utilize a polarized power relay actuated by permanent currents.

A perforating unit and modifications thereof according to the present invention for incorporating in a receiver will now be described with reference to the accompanying drawings wherein:

10 Fig. 1 is a plan view of the said unit;

Fig. 2 is a plan view thereof but with the marking selector and marking elements with which the selector co-operates removed;

15 Fig. 3 is a sectional end elevation on the line III—III, Fig. 1;

Fig. 4 is a development of the cam used in the unit;

20 Fig. 5 is a detail (in end elevation) showing the signal relay and part of means controlled thereby adapted to cause the marking and spacing selectors alternately to assume the co-operative condition relatively to their respective elements and

Fig. 6 is a side elevation of the parts shown in Fig. 5 except the major portion of the relay, the parts in Figs. 5 and 6 being in position to bring about the recording of a marking signal;

25 Figs. 7 and 8 are front and side elevations, respectively, of the said parts at the moment immediately following the reception of a marking signal change;

30 Figs. 9 and 10 are front and side elevations, respectively, of the said parts after the signal change has been accepted;

Fig. 11 is a detail, in plan, showing more particularly the marking selector in co-operative position with respect to the marking elements of the instrument;

35 Fig. 12 is a detail, showing a modification of the unit according to Figs. 1, 2 and 3, the view being in plan and partly in section on the line XII—XII, Fig. 13 which

Fig. 13 is a sectional end elevation of the modified unit shown in Fig. 12, the section being on the line XIII—XIII, Fig. 12;

40 Figs. 14 and 15 are details in end elevation and side elevation, respectively, of part of another modification of the unit;

Fig. 16 is a face view of a latch and its mounting for co-operation with the integers shown in Figs. 14 and 15, the latch being comprised in blocking means operative on the selectors which are modified as shown in Figs. 17 and 18, said selectors being shown adjacent to the said latch and

45 Fig. 17 being a plan view and

2

Fig. 18 an under-plan view, in section on the line XVIII—XVIII, Fig. 16.

The unit shown in Figs. 1, 2 and 3 comprises a base 1 from the ends of which supporting plates 2 and 3 upstand, from the front of which a supporting plate 4 upstands and also from which columns 5 and 6 upstand.

The plate 2 supports the marking punch 7, the spacing punch 8 and the plate 9 containing the tape guide and punch holes, in substantially known manner. The plate 3 carries a bearing 10 for one end of the shaft 11 of a cam 12; the column 6 supports the other end of the shaft. The cam has a punching groove 13 and a selector groove 14; it also has two other grooves for the tape feed mechanism but as this mechanism is not particularly concerned with the invention these two grooves and the said mechanism have been omitted.

The column 5 supports the pivot 15 of punch levers 16 (marking) and 17 (spacing) and the pivot 18 of cranked lever 19 (concerned with marking) and cranked lever 20 (concerned with spacing), said levers 16 and 17 having rollers 21 and 22, respectively, which work in the groove 13 and said levers 19 and 20 having rollers 23 and 24, respectively, which work in the groove 14. The parts of the levers 16, 17, 19, 20 adjacent to the said pivots lie in a slot 25 in the column 5; a cover plate 26 (Fig. 3) secured to the top of the column by screws holds the levers in place on their pivots. Rollers 21 and 23 are above the axis of the cam and the rollers 22 and 24 are beneath it; the axes of the rollers and the cam axis are in the same vertical plane. Therefore, the rollers 21 and 22 are 180° apart in their cam groove and the rollers 23, 24 are 180° apart in their cam groove.

Levers 16 and 17 are connected to punch hammers 27 (marking) and 28 (spacing), one above the other, by push rods 29. The lower hammer is slidably borne by a set screw 30 upstanding from the base 1 and the upper hammer is slidably borne by the lower one. The hammers are transversely slotted at 31, each slot being between the ends of its hammer, and the top of that end of each hammer furthest from its rod 29 is slotted longitudinally at 32. The slots 32 receive the adjacent ends of the punches. The latter are slotted in their undersides at 33 and the disposition of the punches and hammers is such that the claws 34 formed on the ends of the punches by the slotting (33) are engaged by the adjacent ends of the slots 31. Moreover the slots 33 in the punches are of such length, and the slots 31 in the hammers are of such dimension in the direction of the axes of the punches, that the hammers can reciprocate under the influence of the cam groove 13 without driving the punches, i. e., the hammer movements can be lost with respect to the punches.

The said hammer movements can, however, be made sensible on the punches, as will be more fully described hereinafter, by a selector 35 (for marking) and a selector 36 (for spacing). The selectors lie substantially at right angles to the hammers. They have heads 35^a and 36^a, respectively, which normally lie just within the slots 31 and, therefore, are supported at these ends, and have tail portions 35^b and 36^b which are slidably borne in slots 37 and 38, respectively in one edge of the plate 4 (see Figs. 5 to 11). A keeper 39 is secured to this edge of the plate by screws. (The keeper is omitted from Figs. 6, 8, 75

10). A blade spring 40 secured at one end to the plate 4 tends to urge the head 35^a fully into the slot 31 of the marking hammer and a like spring 41 tends to urge the head 36^a fully into the slot 31 of the spacing hammer. When the heads are fully in the slots they lie between the punches and the opposite side of the slot and, therefore, communicate the forward or punching strokes of the hammers to the punches. Return strokes of the punches are effected by the springs 42 around the latter (Fig. 3) and by the action of the hammers on the claws 34. The arrangement may be such that the springs alone return the punches, the claws 34 then being omitted.

The selectors are, however, only allowed to enter their respective slots alternately and then only during certain periods and in response to appropriate signal impulses. This being so the marking and spacing punches are only allowed to operate alternately and then only during certain periods and in response to appropriate signal impulses.

The means compelling alternate operation of the punches during certain periods only and in response to signal impulses comprises the selectors 35, 36, the cranked levers 19, 20 and the cam groove 14; and the means adapted to associate the signal impulses with the above elements comprises a signal-relay operated element 43 having two parallel spring tongues 43^a and 43^b.

The cranked levers are provided at the ends furthest from the cam with rollers 44 and 45. As the levers are alternately rocked by rotation of the cam 12 roller 44 alternately presses on and is removed from the blade spring 40 and roller 45 alternately presses on and is released from the blade spring 41. The rollers press on their respective blade springs alternately and the pressing on periods and the release periods are equal, this being ensured by the profile of the cam groove 14 which consists of two equal but opposite runs as shown in Fig. 4 and by the 180° offsetting of the rollers 23, 24 as previously described. When the rollers press on the blade springs the latter are unable to introduce the heads of the selectors into operative position with respect to the punches.

The element 43 is of bell crank form. It is pivoted to the plate 4 at 46 and has a pin 47 (Figs. 5 to 10) in its depending arm which pin enters a slot 48 in the reed 49 of the signal relay 50. The relay is a polarised power relay actuated by permanent currents. When the reed 49 oscillates in response to signal impulses the element 43 is oscillated within the limits allowed by stops 51.

The spring tongues operate on the tail portions 35^b and 36^b of the selectors. The said tail portions are notched at 52 (Figs. 5 to 10) and normally project outwardly of the outer face of the plate 4. A double armed blade spring 53 secured to the plate 2 normally urges the selectors towards each other so that the selectors are hooked up on the bottom and the top of the slots 37 and 38, respectively, when the tail portions project from the plate 4 to a sufficient extent (see Figs. 1, 6, 8 and 10 more especially). The element 43 is so located that when the top edge of the tongue 43^a is beneath the tail portion 35^b of the marking selector the tongue 43^b is opposite the extremity of the tail portion 36^b and when the bottom edge of the tongue 43^b is above the tail portion 35^b the tongue 43^a is opposite the extremity of the tail portion 35^b.

In operation

The cam is driven from the synchronising shaft of the instrument through a coupling applied to the end 54 of the cam shaft. It is assumed that both selectors are initially hooked up as shown in Figs. 1, 5 and 6. As the cam rotates it alternately rocks the levers 16 and 17 as previously described and alternately rocks the levers 19 and 20. A change from spacing to marking normally arrives when the roller 44 is clear of the spring 40. The signal causes the relay to rock the element 43 clockwise (as viewed in Fig. 5) with the result that the selector 35 is unhooked from the bottom of the slot 37 and the spring 40 is able to drive the head 35^a into the gap between the punch 7 and the opposite or striking face of the punch hammer 21. The parts are then in the position shown in Figs. 9, 10 and 11. The position of the parts at the moment at which the selector 35 is unhooked is shown in Figs. 7 and 8.

The cam 13 then drives the punch hammer, selector and marking punch forward so that a marking hole and a tape feed hole are perforated (the tape feed punch 55 (Fig. 3) being rigid with the hammer 21) and then retracts the hammer. The hammer retracts the selector and the punches 7 and 55.

After perforation of the marking hole the selector head 35^a is withdrawn from its operative position with respect to the punch by the action of the roller 44 on the spring 40 and is finally hooked up owing to the action of the upper blade of the spring 53. This movement of the selector flexes the tongue 43^a.

As will be seen by reference to the parts 43^b and 36^b in Figs. 9 and 10 the tongue 43^b is now in position to unhook the selector 36. This it does when a change from marking to spacing normally occurs; and when the selector 36 is unhooked its head 36^a is driven into operative position with respect to the punch 8 by the spring 41, said spring having been released by the roller 45. A spacing hole is then punched, the corresponding punch hammer 28 and the selector 36 and punch 8 are retracted, the selector being again hooked up owing to the action of the roller 45 on the spring 41 and to the action of the lower blade of the spring 53 on the selector 36. The parts are again in the position shown in Figs. 1, 2, 3, 5 and 6 and the operations can be repeated in the sequence marking, spacing, marking, spacing and so on but owing to the alternating action of the tongues 43^a and 43^b a spacing hole must always follow a marking hole and vice versa, i. e., it is not possible to miss one signal without the other.

The marking selector may be unhooked during interval 3-4, for example, but will be unable to enter the operative position with respect to the marking punch because the spring 40 will still be immobilised by the roller 44. If the signal is of normal length it may therefore arrive shortly after moment 2 so long as it extends a fraction of time beyond moment 3 when it will be picked up. It may also be delayed so that it does not start until just before moment 4. As each interval between moments denoted by successive numerals correspond to 180° motion of the cam 14, it can be said that the pick up range is approximately 360°.

If a fortuitous distortion such as a break in a dot should occur whilst the spring 40 is freed by the roller 44 (i. e., during a marking period) the element 43 will be rocked anti-clockwise owing to the change in polarity from marking to spacing.

The spacing selector will consequently be unhooked but the spring 41 will be immobilised by the roller 45 and, therefore, the change will not be accepted by the instrument. The second constituent of the break will then occur, i. e., there will be a change from spacing to marking and the element 43 will be restored to its original position, allowing the selector to be hooked up again. It is thus seen that the break in the signal will not be registered. Even if there were several such breaks during the blocked interval, none would be registered.

In a modification of the invention the punch hammers may be reciprocated by a cam groove as 14, Fig. 4, whilst the cam groove 13 and the levers 19 and 20 are dispensed with, withdrawal of the selectors from their operative position with respect to the punches being effected by fixed ramps. Such an arrangement will now be described with reference to Figs. 12 and 13.

In Figs. 12 and 13 the tail portions of the marking and spacing selectors 56 and 57, respectively, are similar to those of the selectors 35 and 36 but the heads of the selectors are shouldered near their extremities as at 58. The hammers 27 and 28 slide in recesses in a column 59 fixed to the base 1 and the column carries ramps 60 which lie in the paths of movement of the shoulders 58 when these latter, once the ends of the heads of the selectors 56 and 57 are in the gaps between the punches and the opposite faces of the hammers, advance with the hammers. Springs as 40 and 41 (Fig. 1) tend to urge the said heads into the said gaps. For the first 180° of cam movement the marking hammer is in a forward position. Therefore, the back end of the punch prevents the heads of selector 56 from entering its gap during this period. For the second 180° of cam movement the head of selector 57 is blocked out of its gap in similar manner by the punch 8. However, the marking selector head can enter the gap between the punch 7 and the opposite face of the hammer 21 when the latter is in its rear position and the spacing selector head can enter its gap when the hammer 28 is in its rear position. In other words the said heads are alternately blocked out of their respective slots for equal periods.

When a marking signal is received the selector 56 is unhooked by the tongue 43^a and provided the hammer 27 is in its rear position the head of selector 56 enters the gap behind the punch. The hammer, head and punch are then driven forward and whilst this takes place the head is withdrawn from the gap owing to engagement of the shoulders 58 on the said head with the upper and middle ramps 60. The ramps cause it to take a position where the spring 53 can again hook it up. When a spacing signal follows, the selector 57 is unhooked, a spacing hole is perforated and the middle and lower ramps 60 and the spring 53 cause the said selector to be hooked up again in a manner comparable with that described with reference to the selector 56.

The heads do not entirely leave the slots 31 in the hammer's and, therefore, reciprocate with the hammers continuously.

A further modification of the invention will now be described with reference to Figs. 14 to 18. In this modification the alternate blocking out of the selectors is effected by an H-shaped latch 61 co-operating with detents 62 and 63 on the selectors 64 and 65, respectively; and a simple bell crank lever 66 is used instead of an element as 43, Fig. 1.

The punch hammers as 27 and 28 are reciprocated by means comprising a cam groove 13 as described with reference to Figs. 1 and 2 and the selectors 64 and 65 are urged into the slots 31 in the hammers and withdrawn from them by springs as 40 and 41 controlled by levers 19 and 20, Figs. 1 and 2. The levers are controlled by a cam groove as 14. A spring as 53 (Figs. 1 and 2) is omitted as the selectors are not hooked up on the plate 4; the tail portions of the selectors simply slide in the slots 37 and 38 and are hooked up by the lever 66.

The bell crank lever 66 when in the position shown in Figs. 14 and 15 engages a notch 68 in the tail of the spacing selector and when in the other extreme position engages a notch 69 in the tail of the marking selector. The lever 66 is oscillated by a relay as 50, Fig. 5, the reed of which relay engages the pin 10 on said lever and the relay is arranged to rock the lever 66 as viewed in Fig. 14 counter clockwise for marking signals and clockwise for spacing signals.

The latch 61 is pivoted at its centre to a plate 71 which is secured to a base as 1 in such a position that when the selectors are in their rear positions (i. e., the positions wherein they are not advanced by the hammers) the axis of the detent 62 is in line with a spring loaded ball 72 and the axis of the detent 63 is in line with a spring loaded ball 74, the balls being mounted in the plate 71. The latch is located between the plate and the punch hammers. The balls act as clicks which balls by engaging the sides of the gaps in the latch hold it either in the position shown in Figs. 16, 17 and 18 where the ball 72 projects slightly into the upper gap whilst the limb 61^b of the latch lies between the ball 74 and the detent 63, or in the position where the ball 74 projects slightly into the lower gap whilst the limb 61^a of the latch lies between the ball 72 and the detent 62.

As the punch hammers reciprocate they carry the heads of the selectors with them. In addition the springs as 40 and 41 controlled by the bell crank levers as 19 and 20 tend to cause reciprocation of the selectors.

As marking and spacing signals (with perfect timing) arrive in succession the detent 62 enters the upper gap in the latch and by engagement with the limb 61^c thereof trips the said latch to its alternative position. The detent is withdrawn from the gap before it returns with the hammer by the action of the bell crank lever as 19. A spacing signal then causes the lever 66 to release the spacing selector 65 so that this can be driven into the lower gap. The selector 65 trips the latch to its original position by engaging the limb 61^d thereof and before returning with the hammer is withdrawn from the gap by the bell crank as 20. Every time a detent enters a gap in the latch the head of the selector is able to attain its operative position with respect to the punch. Therefore, punching is effected. The spacing signal causes the lever 66 to engage the marking selector but the following marking signal releases the said selector and causes the lever to engage the spacing selector. And so on. Thus, signals are recorded in the order marking, spacing, marking, spacing, and so on but fortuitous distortions cannot be recorded as during possible marking signal accepting periods the detent 63 is blocked by the limb 61^b and during possible spacing signal accepting periods the detent 62 is blocked by the limb 61^a, marking signal accepting periods occurring during 180° of cam rotation and spacing signal accepting periods 75

occurring during the next 180° of cam rotation and so on.

In the case of signals longer than a dot, such as dashes, holes should only be perforated at each change of polarity in the signals, and the sequence will be as follows: The marking selector will first be released by the lever 66 and the spacing lever arrested by the same lever. The marking punch will perforate a hole in the tape, and the latch 61 will be thrown so that limb 61^a covers ball 72. During the second half revolution spring 41 will urge the spacing selector 65 forward but this selector is prevented from moving by the locking action of the lever 66, consequently no further movement of the selector takes place. During the third half revolution the marking selector 64 is urged forward by spring 40 but is prevented from causing a perforation of the tape by detent 62 hitting against limb 61^a. Not until the fourth half revolution will a perforation take place, namely of a spacing hole which follows on the release of the spacing selector by lever 66 being operated by the change marking—spacing occurring at the end of the dash signal.

The selectors may be operated by individual relays.

The invention may be applied to telegraph receivers of any suitable kind operating on the Wheatstone (Morse) system of signalling.

What I claim is:

1. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, a cam synchronised to the signals, mark and space means, means operable by said cam to actuate said mark and space means, selectors operable by said cam to control the actuation of said mark and space means and means whereby the relay also controls the selectors whereby signals received at correct times permit movement of the 40 selectors by said cam to effect operation of the mark or space means.

2. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, a cam synchronised to the signals, mark and space means, actuators for said mark and space means operated alternately by the cam, selectors to control operation of the mark and space means by said actuators, springs acting to move said selectors into operative positions, selector control means operated by said cam alternately with said actuators and adapted to free the selectors for movement by said springs and means to further control the movement of said selectors from said relay whereby said selectors are free to move to operative positions only on receipt of a correctly timed signal.

3. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, a cam synchronized to the signals, mark and space punches, strikers operable by said cam to actuate

said mark and space punches alternately, mark and space selectors operable alternately by said cam to control the actuation of said mark and space punches respectively, latch means to retain said selectors in non-operative positions and means whereby the relay also controls the release of said selectors from said latch means whereby signals received at correct times permit movement of the selectors by said cam to effect operation of the mark or space punches.

4. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, a cam synchronised to the signals, mark and space punches, actuators for said mark and space punches operated alternately by the cam, selectors to control operation of the mark and space punches by said actuators, springs acting to move said selectors into operative positions, selector control means operated by said cam alternately with said actuators and adapted to free the selectors for movement by said springs, latch means to prevent movement of such selectors and means actuated by said relay to control the unlatching of said selectors to make them free to move and whereby they move by said springs to their operative positions only on receipt of a correctly timed signal.

5. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, a two part cam synchronised to the signals, mark and space punches, independent actuators for said mark and space punches operated alternately by one cam part, mark and space selectors to control operation of the mark and space punches by said actuators, springs acting to move said selectors into operative positions, mark and space selector control means operated by the other cam part alternately with said actuators and adapted to permit the selectors to move by said springs, latch means to retain said selectors in inoperative position and means to control the release of said latch means from said relay, whereby a selector, released on receipt of a signal, only moves into operative position if permitted by the control means and only for a correctly received signal.

6. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, a two part cam synchronised to the signals, mark and space punches, independent actuators for said mark and space punches operated alternately by one cam part, mark and space selectors to control operation of the mark and space punches by said actuators, springs acting to move said selectors into operative positions, mark and space selector control means operated alternately by said cam said operations occurring alternately with said actuators and timed to provide a possible period of cooperation of the mark selector, actuator and punch which is equal to and alternate with a possible period of cooperation of the

space selector, actuator and punch, means to retain said selectors in inoperative positions and means operated by said relay to free said selectors to permit them to move to operative positions when permitted by the selector control means.

7. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, mark and space punches, mark and space selectors in cooperative relation therewith, mark and space strikers for said punches acting through the intermediary of said selectors when in operative positions, a cam synchronised to the signals, means operated by said cam to operate the mark and space strikers alternately, further means operated by said cam to move alternately said mark and space selectors out of the operative positions in relation to the respective punches and strikers, spring means acting to move the selectors into the operative positions, means to retain the selectors in positions where the strikers are inoperative to act on the punches and means controlled by the signal relay to determine the release of said selectors to permit them to move alternately under the control of the said further means, so that a correctly received signal releases the appropriate selector at the same time that said selector is allowed to move by the said further means.

8. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, mark and space punches, mark and space selectors movable into cooperative relation therewith, mark and space strikers for said punches acting through the intermediary of said selectors when in operative positions, a cam synchronised to the signals, cam followers engaging said cam to operate the mark and space strikers alternately so that such strikers are operated at cyclic intervals when mark and space conditions could occur with a correctly received signal, further cam followers engaging said cam to move said mark and space selectors alternately one with the other and alternately with the movement of the strikers such movement of the selectors being out of the operative positions in relation to the punches and strikers, spring means acting to move the selectors into the operative positions, latch means to retain the selectors in inoperative positions where the strikers are inoperative to act on the punches and means controlled by the signal relay to determine the release of said selectors to permit them to move alternately under the control of the further cam followers, the latter being timed by the cam in relation to a train of received signals so that a correctly received signal releases the appropriate selector at the same time that said selector is allowed to move by the cam follower concerned.

9. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, mark

11

and space punches, mark and space selectors movable into cooperative relation with said punches respectively, mark and space strikers for said punches acting through the intermediary of said selectors when in operative positions, a cam synchronized to the signals, cam followers engaging said cam to operate the mark and space strikers alternately so that such strikers are operated at intervals when mark and space conditions respectively could occur with a correctly received signal, further cam followers engaging said cam to move said mark and space selectors alternately one with the other and alternately with the movement of the strikers such movement of the selectors being out of the operative positions in relation to the punches and strikers, spring means acting to move the selectors into the operative positions, latch means to retain the selectors in inoperative positions where the strikers are inoperative to act on the punches and means controlled by the signal relay to determine the release of said selectors to permit them to move alternately under the control of the further cam followers, the latter being timed in relation to the received signals so that a correctly received signal releases the appropriate selector at the same time that said selector is allowed to move by the cam follower concerned and before the relevant striker operates to actuate the corresponding punch.

10. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, mark and space punches, mark and space selectors movable into cooperative relation therewith, mark and space strikers for said punches acting through the intermediary of said selectors when in operative positions, a shaft synchronized to the signals, a first cam on said shaft, followers engaging said cam to operate the mark and space strikers alternately, a further cam on said shaft, further followers engaging said further cam to move said mark and space selectors alternately at time intervals intermediate between the operation of the first-named followers by said first cam such movement of the selectors being out of the operative positions in relation to the punches and strikers, spring means acting to move the selectors into the operative positions, latch means to retain the selectors in inoperative positions where the strikers are inoperative to act on the punches and means controlled by the signal relay to determine the release of said selectors so that a selector released by a correctly timed signal moves to the operative position whereas a selector released by an incorrectly timed signal, is freed at a moment when movement is prevented by the appropriate further follower.

11. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, mark and space punches, mark and space selectors movable into operative positions in cooperative relation therewith or into a disengagement position, mark and space strikers for said punches acting through the intermediary of said selectors when in operative positions, a shaft syn-

12

chronized to the signals, a first cam on said shaft, followers engaging said cam to operate the mark and space strikers alternately, a further cam on said shaft, further followers engaging said cam to permit disengagement of said mark and space selectors alternately and for equal time periods, the movement of the strikers being timed to occur in course of periods alternating with the periods of disengagement, spring means acting to move the selectors into the operative positions, latch means to retain the selectors disengaged independently of said followers and means controlled by the signal relay to determine the release of said selectors from said latch means to permit them to move if so permitted by the further followers.

12. In a telegraphic receiving instrument for code signals for the Wheatstone (Morse) land line system of signalling in which each code element is an uneven multiple of the shortest signal and hence changes from spacing to marking can only occur at different instants from marking to spacing, a relay responsive to received signals, mark and space punches, mark and space selectors movable into operative positions in cooperative relation therewith or into a disengagement position, mark and space strikers for said punches acting through the intermediary of said selectors when in operative positions, a shaft synchronized to the signals, a first cam on said shaft, followers engaging said cam to operate the mark and space strikers alternately, a further cam on said shaft, further followers engaging said cam to permit disengagement of said mark and space selectors alternately and for equal time periods, the movement of the strikers being timed to occur in course of periods alternating with the periods of disengagement, spring means acting to move the selectors into the operative positions, latch means to retain the selectors disengaged independently of said followers, means controlled by the signal relay to determine the release of said selectors from said latch means to permit them to move if so permitted by the further followers, a paper guide to present paper in punching position in relation to said punches and means operated by said shaft to feed such paper in stepwise manner.

13. In a telegraphic receiving instrument for code signals for the Wheatstone (Morse) land line system of signalling in which each code element is an uneven multiple of the shortest signal and hence changes from spacing to marking can only occur at different instants from marking to spacing, a cam synchronized to the signals, mark and space punches, strikers operable by said cam to actuate said mark and space punches alternately, mark and space selectors, said selectors being notched near their free ends, springs acting to move said selectors axially to a position providing cooperation between the strikers and the punches, a latch plate having apertures the edges of which are engageable by the notched parts of the selectors to retain the selectors in retracted positions, means operated by said cam to move said selectors alternately and against the action of said springs into the said retracted positions, a signal relay, an element operated thereby and movable in a plane intersecting the ends of the selectors, and flexible tongues on said element engageable with said selectors, the overall width of said tongues being greater than the distance between the selectors so that at every instant when the selectors are retracted one tongue is flexed by the end of one selector and the other tongue is positioned to release the other selector

on operation of the relay from the latch plate and the range of movement of said element being such that only after that other selector has been released and has been moved forward by the action of the cam, can the said element complete its movement to a position permitting the former tongue to move off the end of the former selector into a position which permits the former selector to be unlatched on the next operation of the relay.

LEIF CHRISTIAN OLSEN.
